HEAT EXCHANGER

Karl Muhleisen, Philadelphia, Pa., assignor to
 Schutte & Koerting Company, Philadelphia,
 Pa., a corporation of Pennsylvania

Application December 1, 1934, Serial No. 755,671

2 Claims. (Cl. 257—239)

In a heat exchanger there is usually provided a tube sheet loose in the shell and carried by one end of the tubes and a flanged head secured to the tube sheet and together with it, serving to separate the two fluids, of which the pressure of at least one is above atmospheric pressure. It is one object of the present invention to prevent commingling of the two fluids by leakage at the joint between the flanged head and the sheet and to this end, generally stated, the invention comprises an annular open groove provided at the joint and having pipe connections to the exterior of the exchanger.

Other objects of the invention will appear from the following description at the end of which the invention will be claimed.

In the following description reference will be made to the accompanying drawing forming part hereof and in which,

Figure 1 is a view partly in elevation and partly in section of one form of heat exchanger, selected from among other forms, and embodying features of the invention, and

Figure 2 is a detached illustration of a modification.

Referring to the drawing, 1 is a tube sheet carried by the tubes 2 and movable in the casing 3 to allow for contraction and expansion. 4 is a flanged inner head secured to the tube sheet as shown by bolts 5. Between the flange of the inner head 4 and the tube sheet there is shown a gasket 6. One fluid enters the casing, for example at 7, and leaves it at 8 flowing around the outside of the tube. The other fluid enters the casing as at 9 and flows through some of the tubes toward the inner head 4 and then back through the rest of the tubes leaving the casing at 10. It is evident that the joint between the tube sheet 1 and the flange of the inner head 4 serves to prevent commingling of the two fluids so that if the joint should leak the fluids would commingle which, of course, is very undesirable. According to the present invention this is prevented by the provision of an annular groove 11 between the inner head 4 and the tube sheet 1. This groove may be provided in the flange of the inner head 4, as shown in Figure 1, or in the tube sheet 1, as indicated in Figure 2. In either case there is a pipe connection to the exterior of the shell 3 from this groove. In Figure 1 the pipe connection is shown at 12 and it extends more or less

parallel with the tubes. As shown in Figure 2 this pipe connection 12a extends away from the tubes and is packed by a gland 13 through which it is afforded some range of movement. In either case the pipe connection 12 or 12a serves to convey the fluid of higher pressure, which is the fluid which will leak into the annular groove, out of the casing, and in that way prevent it from commingling with the other fluid. The pipe 12 or 12a not only serves the purpose indicated but also acts as a tell-tale and indicates from the outside of the casing the occurrence of leakage.

It will be obvious to those skilled in the art to which the invention relates that modifications may be made in details of construction and arrangement without departing from the spirit of the invention, which is not limited as to such matters or otherwise than the prior art and the appended claims may require.

I claim:

1. A heat exchanger comprising in combination, a casing, a plurality of aligned tubes within said casing, an inner tube sheet carried by said tubes and movable relative to said casing, an inner head having a domed portion spaced from said inner tube sheet and opposite said tubes and having a peripheral flange thereon forming a joint with said inner tube sheet, an annular groove formed in said joint between said tube sheet and said inner head and encircling the ends of said tubes, a pipe forming a drain from said groove and extending through said casing, and a gland sealing said pipe to said casing where said pipe passes through said casing and affording limited movement to said pipe relative to said casing.

2. In a heat exchanger having a casing and a plurality of tubes in said casing, a floating tube sheet construction comprising, an inner tube sheet, an inner head secured to said tube sheet and having a portion spaced from said tube sheet to provide a passageway for fluid therebetween and having a portion forming a sealing joint with said tube sheet, an annular groove in said joint between said tube sheet and said head and encircling said passageway to receive fluid leaking toward or away from said passageway, and means communicating with said groove and extending through said casing and providing a drain for said groove.

KARL MUHLEISEN. 50
